UNITED STATES PATENT OFFICE.

GEORGE GEBHARDT, JR., OF NASHVILLE, TENNESSEE.

COUNTER BLOCK FOR EMBOSSED PRESSES.

1,411,011.

Specification of Letters Patent. Patented Mar. 28, 1922.

Application filed August 5, 1921. Serial No. 490,048.

To all whom it may concern:

Be it known that I, GEORGE GEBHARDT, Jr., a citizen of the United States, residing at Nashville, in the county of Davidson and State of Tennessee, have invented certain new and useful Improvements in Counter Blocks for Embossing Presses, of which the following is a specification.

This invention relates to improvements in embossing presses and more particularly to an improvement in the construction of the counter block and counter which supports the male die.

The usual practice in making ready for the operation of an embossing press is to prepare the female die in the usual manner and then, after preparing the counter or male die, to secure the counter by glue or other similar means to the face of the counter block or counter block slide. Then after the required number of impressions have been made the female die is preserved for future use in the event a reprint is required, but the male die is destroyed at the time it is removed from the face of the counter block or counter block slide. As the preparation of the male die or counter requires considerable time and labor, a corresponding amount of time and labor must be lost in the event a reprint is ordered. It is, therefore, the primary object of the present invention to provide means whereby the male counter or die may be mounted upon the counter block or counter block slide in a manner to permit of its removal therefrom without destruction or mutilation and so that it may be preserved in the same manner as the female die, for future use. In this manner the expense which would otherwise be involved through the labor of an embossing pressman in repreparing the male die, as well as the time lost while the embossing press remains idle, is saved.

In the accompanying drawings;

Figure 1 is an inverted perspective view of the device embodying the present invention;

Figure 2 is a vertical front to rear sectional view through the device;

Figure 3 is an inverted perspective view of the counter block slide removed from the counter block;

Figure 4 is a vertical transverse sectional view through the counter block slide.

In the drawings the numeral 1 indicates in general the counter block, which is pro-

vided with the usual shank 2 whereby it may be secured to the die plunger of an embossing press. The improvements embodying the invention may be adapted directly to the block 1 or to a counter block slide as illustrated in the drawings, this slide being indicated in general by the numeral 3 and comprising a plate 4 having its end edges beveled as indicated by the numeral 5 so as to engage the under cut or beveled edges of guide strips 6 secured upon the under face of the block 1 at the ends thereof. When the counter block slide 3 is employed, it is slid into place upon the face of the block 1 and secured against displacement by lugs 7 upon the forward edge thereof which engage the corresponding edge or face of the block, and by a binding screw 8 which is threaded into the said face of the block and may be tightened to clamp in place a locking plate 9 which over-laps the said forward edge of the slide 3.

The male counter or die is indicated in general by the numeral 10 and the same comprises a rectangular sheet 11 of card-board upon the face of which the die proper, indicated by the numeral 12 is built up in the usual manner. As stated above, the counter board or die 10 is usually glued or secured in a similar manner directly to the face of the counter block 1 or to the face of the counter block slide 3 and, after the required number of impressions have been made, is removed therefrom and in the course of removal is mutilated or destroyed. Inasmuch as the present invention however contemplates such removal without mutilation or destruction, means is provided for holding the counter board or die 10 assembled with the slide 3 in a manner to permit of its instant separation and replacement when required. With this end in view the invention contemplates the provision along the rear edge and both end edges of the face of the slide 3, of retaining members designed to marginally engage the counter board or die 10 and thus serve the purpose stated. The flange at the rear edge of the face of the counter block slide is indicated by the numeral 13 and the flanges at the end edges thereof are indicated by the numeral 14 and each of these flanges comprises a strip 15 of metal having one edge rabbeted as at 13 to provide a groove 17 and an over-hanging lip 18 to receive and engage the rear and end edges of the sheet 11 of the counter

board. Thus when the board has been prepared in the usual manner, it is slid into engagement with the flanges 13 and 14, and after the required number of impressions 5 have been made, the counter board may be readily slid from engagement with the slide 3 without mutilation or destruction and filed away for future use. It will be understood that the strips 15 comprising the flanges 13 10 and 14 may be made integral with the face of the slide 3 or secured to the face of this slide in any suitable manner, as for example by screws 19 fitted through the upper side of the slide and threaded at their lower ends 15 into openings formed at suitable intervals in said strips. It will be also understood that if desired the slide 3 may be dispensed with and the strips 15 may be arranged in a similar manner upon the face of the counter block 1.

It will be understood that instead of the strips 15, any other suitable means may be

employed for temporarily holding the counterboard 10 upon the face of the counter.

Having thus described the invention what 25 is claimed as new is:

1. In a device of the class described, in combination with the counter block of an embossing press, a counter block slide held thereto, a die embodying a base sheet disposed against the face of the counter block slide, and means removably securing the sheet in place.

2. In a device of the class described, in combination, a male counter comprising a 35 sheet of cardboard or its equivalent and a die portion built up upon the face thereof, a counter block slide against the face of which the said sheet is disposed, and means carried by the said slide removably retaining the said counter sheet.

In testimony whereof I affix my signature.

GEORGE GEBHARDT, JR. [L.S.]
